DISCONNECT SWITCH

William O. Schultz, South Milwaukee, and Alwin G. Steinmayer, Milwaukee, Wis., assignors to Line Material Company, Milwaukee, Wis., a corporation of Delaware

Original application June 16, 1939, Serial No. 279,414. Divided and this application May 25, 1940, Serial No. 337,194

8 Claims. (Cl. 200—162)

This invention relates to disconnect switches for use in electrical distribution systems and designed for mounting out-of-doors on transmission line poles. Such a switch is ordinarily enclosed within a porcelain housing and has a door hinged at the top to provide access to the switch; and the opening and closing of the switch is generally accomplished by means of a non-conductive hooked pole manipulated by a lineman who must climb the pole to get within reach of the switch. Because such switches frequently carry very heavy currents it is important that the contact pressures be high; and due to the fact that a switch may remain closed continuously for long periods of time while subjected to corrosive atmospheres causing the contacts to oxidize and adhere, it has been found desirable, especially on the larger switches, to provide, in conjunction with the switch blade, a movement-amplifying lever mechanism which will function to break open the contacts without requiring a greater amount of force than a lineman can easily exert while maintaining his balance on a pole.

Our present invention has to do with improvements in disconnect switches of the type above referred to and has two primary objects. One object is to achieve a maximum degree of compactness whereby to reduce the size and cost of the porcelain housing and Bakelite door, while at the same time proportionately reducing the weight and the size of the package required for shipping and the space required for storing. The second object is to provide a disconnect switch in which the operating lever when in closed position can be more easily seen and reached by a lineman standing on a pole beneath the switch—and frequently also far to one side of the switch.

The prior art discloses several knife-blade switches having movement-amplifying levers carried by the main switch blades at the free extremities thereof and there is presently on the market a housed disconnect switch having a main switch blade and a movement-amplifying lever likewise mounted at the extreme free end of the main blade. But in order to construct a housed disconnect switch in that manner and realize a desirable amount of amplification while at the same time providing for adequately breaking the high pressure contacts, it is necessary to extend the housing upwardly or else resort to a system of compound levers which complicates and increases the cost of the structure.

Pursuant to the above recited objects, our

improved disconnect switch is characterized by the inclusion of a simple movement-amplifying lever mechanism which is carried by the switch-blade and pivoted thereto at a point midway of the length of the blade and remote from the upper end of the housing; and said mechanism is capable of providing the necessary degree of amplification of movement to bring about easy disengagement of the contacts, as well as adequate initial separation of the contacts, thus ensuring that the lineman will be able to complete each switch-opening operation without undue effort while at the same time maintaining proper separation between switch terminals and reducing the overall length of the housing.

A second feature of our invention consists in the provision of a switch operating arm which projects outwardly from the interior of the switch-containing porcelain box into a recess in the housing door and well beyond the front edge of the porcelain box so that when the door is open said arm is completely and readily accessible and can be engaged by a hooked pole in the lineman's hand with a maximum of convenience; yet when the door is closed the entire switch structure including said arm is under cover. This second feature is applicable whether the disconnect switch is provided with a movement-amplifying lever mechanism or otherwise.

While the present invention contemplates, more especially, improvements in housed disconnect switches, it is usefully applicable also to un housed switches, as will be apparent from the description which follows.

The present application is a division of our copending application, Serial Number 279,414, filed June 16, 1939, entitled "Quick-break disconnect switches."

In the drawings:

Fig. 1 is a view in side elevation, partly in section, showing a housed disconnect switch embodying this invention.

Fig. 2 is a view similar to Fig. 1 showing the switch moved toward open position.

Like parts are identified by the same reference characters throughout the several views.

The housing for the switch comprises a box-like casting of insulating material, such as wet process porcelain, which is moulded to form a relatively thick rear wall 1, a top wall 2, side walls 3, and bottom wall 4 having a recess 5.

A door 6, made of insulating material such as "Bakelite," is pivotally mounted at its upper end adjacent the top wall 2 within the recessed portion 7. The pivot for the door may comprise

a pin 8 extending through the walls 3 and hub portion 9 on the door. Disposed on pin 8, at each end of hub portion 9, are a resilient friction plate 10 and pressure member coacting to resist pivotal movement of the door, thus providing means for retaining the door in open position extending horizontally from the housing as indicated in Fig. 2. The means for retaining the door in elevated position has not been shown in detail, since any suitable means may be provided for obtaining the desired result.

The rear wall 1 of the housing is provided with spaced terminal supports 15 and 16 anchored in recesses 17 by means of cement or other desirable material 18 and with a switch-blade support 19 spaced from the support 16 and anchored in recess 20 by means of cement 21. Secured to the outer face of the rear wall 1 by any desirable means, such as bolts 22 anchored in the wall, is a pivot plate 23 having its ends 24 bent angularly to coact with similar ends on the mounting strap 25. The corresponding ends of plate 23 and strap 25 are pivotally connected by means of bolts 26 and are normally held against relative pivotal movement by means of nuts 27. The strap 25 is provided with bolts 28 cooperating with other parts, not shown, for attaching the housing to a cross-arm, not shown. Disposed between the terminal supports 15 and 16, is a barrier 29 which increases the leakage distance between the supports.

The side walls 3 of the housing are each provided with spaced holes, not shown, adjacent terminal members 31 and 32 for insertion of line wires, not shown, to be connected with the terminals in the manner hereafter more fully disclosed.

Terminal members 31 and 32 are identical and, as may be clearly seen in Fig. 2, each comprises a base 34 having a contact plate or blade 35 normal thereto and extending along a central portion thereof, wing portions 36 at opposite sides of plates 35 and each having an aperture 37, clamping jaws 38 disposed on opposite sides of the plate 35 and spaced from adjacent wing portions 36, and spaced legs 39. As may be clearly seen in Fig. 2, each contact plate 35 is L-shaped to provide a narrower portion 40 which serves as a camming surface more fully described hereinafter.

Terminal members 31 and 32 are loosely mounted on terminal supports 15 and 16, respectively, to obtain a full-floating effect permitting lateral and angular alignment thereof relative to the supports and with the switch blades subsequently more fully described. This mounting is secured by means of sleeves 41 which fit loosely in apertures 37 in the terminal members. The sleeves are rigidly retained on supports 15 and 16 by means of bolts 42 which extend through the sleeves and are threaded into the supports.

The upper terminal member 31 is retained on the sleeves by means of a washer 44 and the head of the bolt 42. The length of each sleeve 41 is greater than the distance between the bases of legs 39 and faces of wing portions 36 on terminal member 31, thereby permitting movement of the member between washer 44 and support 15.

Lower terminal member 32 is secured to support 16 in a similar manner described with reference to upper terminal 31. Disposed between terminal members 31 and 32 and supports 15 and 16 are rectangular arcuately bent plate springs 43, which serve to hold the members outwardly of the supports and in contact with washers 44 and 47, respectively.

Mounted on each of the clamping jaws 38 is a movable clamp 50 having an elongated opening 51 receiving jaw 38 and provided with a clamp-actuating bolt 52 extending into and lengthwise of opening 51 for actuating engagement with jaw 38. The bared ends of conductors, not shown, may be passed through the holes in sides 3 of the housing and inserted between the cooperative clamping surfaces on jaws 38 and clamps 50 and clamped thereby upon appropriate manipulation of bolts 52.

Terminal members 31 and 32 may, for convenience of description, be denominated "fixed contact members" to distinguish clearly from the switch-blade, which is a movable contact member.

The switch blade comprises a pair of spaced, parallel, flat bars 53 and 54 which are pivotally mounted at the lower end of the housing on a pivot bolt 55 which extends through bars 53 and 54 and support 19, and is secured in such position by means of a nut 56 and lock nut 57. The upper ends of bars 53 and 54, as viewed in Figs. 1 and 2, are connected by a bolt 59 which extends through the bars and is held in position by means of a nut 60. Preferably, the nut 60 is secured in position by mutilating the threads on the bolt, and cupped washers 61 are provided to give a degree of resiliency and for maintaining the bars in high pressure engagement with the contact 35 on upper terminal member 31.

Passing laterally through bars 53 and 54 at a point below the upper fixed terminal is a bolt 62 on which are mounted cupped washers 64 bearing against said bars under the influence of a nut 63 and the head of the bolt—said bolt, washers and nut serving to press bars 53 and 54 into yieldable, tight, frictional engagement with terminal contact member 35.

Below bolt 62, as viewed in Figs. 1 and 2, and above the contact 35 on the lower terminal member 32, is a bolt 65 which extends through bars 53 and 54. A nut 69 retains bolt 65 in position. This bolt serves to hold the bars in firm frictional engagement with contact 35 on lower terminal member 32.

Pivottally mounted on bolt 65 and between bars 53 and 54, is a switch-operating lever 70 of the first class having at its upper end a pull-push ring 71 extending from between the bars, a cam finger 72, and stop finger 73 engageable with a pin 74 which extends through bars 53 and 54 and is retained in position by means of a washer 75 and cotter pin 76.

A coil spring 78 positioned between bars 53 and 54 is engaged at one end with pin 74 and at the other end with the apertured lug on lever 70. This spring normally maintains lever 70 in the position shown in Fig. 1 and against bolt 62.

When it is desired to move the switch from closed position, shown in Fig. 1, door 6, which is provided with a recess 6A for receiving pull ring 71, will be first moved to the position indicated in Fig. 2. Pull ring 71 on lever 70 will be engaged by a suitable operating stick, not shown, and thereby pulled from between bars 53 and 54. As lever 70 is pulled in the manner indicated, cam finger 72 at the lower end thereof engages the portion 40 on lower terminal member 32. Pressure thus applied to member 32 will first cause said member to assume substantially the position shown in Fig. 2, and thereafter cause the switch blade to move outwardly about the pivot bolt 55 to the position shown in Fig. 2 where the switch 75 is out of engagement with contact member 35.

on upper terminal member 31. When the switch has reached substantially the position shown in Fig. 2, stop finger 73 on lever 70 will engage pin 74 and thereafter the switch will be moved directly by means of the lever to complete open circuit position, not shown, where the switch will extend downwardly from the pivot bolt 55 into recess 5 where it will be insulated from terminal members 31 and 32.

As previously noted, terminal members 31 and 32 are in effect floating on the terminal supports 15 and 16, respectively. This permits members 31 and 32 to assume various positions during closing and opening movements of switch bars 53 and 54 and thereby affords efficient and smooth operation of the switch.

It may be noted that as the cam finger 72 is forced against portion 40, terminal 32 is slightly rotated about the sleeve mountings 41, thereby breaking loose any oxide coating which may have formed on the parts and which tend to hold the contact blades 35 in rigid relation with bars 53 and 54. It may also be noted that the mechanical advantage of the lever allows an operator to move the switch to open circuit position with a minimum of effort.

When the switch is in open position, door 6 may be closed to prevent accidental contact with the live portions in the housing and to prevent small birds from attempting to rest on such portions.

In housed disconnect switches of the prior art the movement-amplifying switch-operating means corresponding to lever 70 and cam finger 72 have been placed at the free extremity of the switch-blade—projecting upwardly therefrom—and have, accordingly, required a considerable upward extension of the housing in order to provide necessary clearance. By moving the switch-operating means down and pivoting it at an intermediate point on the switch-blade, as herein illustrated and described, we are able to effect a substantial reduction in the length of the housing and door while at the same time incurring no sacrifice with respect to effectiveness of the switch-operating means. Although a greater force is required to open the switch when that force is applied to the switch-blade at an intermediate point, as in our structure, instead of at the free extremity of the blade, the additional force requirement is offset or more than offset by the greater leverage ratio which is made possible. It will be observed that a smaller angular movement of lever 70 is required to disengage the contacts than would be the case if the switch-operating means were moved up to or toward the free end of the switch blade.

In our switch structure, it will be noted, ring 71 is well below the upper end of the housing—which is a distinct convenience to the lineman—and very adequate leverage advantage obtains.

So far as unhoused disconnect switches are concerned it may be generally immaterial whether the movement-amplifying lever is connected to the switch-blade at its extremity or at an intermediate point; but where conservation of overhead clearance space or limitation of overall length are material factors, our structure has a distinct advantage which is not limited to housed switches.

Another advantage in our switch structure, from the lineman's point of view, is that ring 71 projects beyond the front edge of the porcelain box. Thus, when the door is open, the lineman, who may be standing on the pole to one side and below the switch, has no difficulty in seeing the

ring and engaging it with the hook end of a switch stick. While this may seem like a minor feature, it is nevertheless a thing of real consequence when adverse conditions obtain, such as darkness and snow storms.

We claim:

1. In a disconnect switch, a housing having an interior chamber and comprising a box made of insulating material and having a frontal opening leading into said chamber, said housing including a displaceable door for said opening, said door providing access to said chamber, and switch structure disposed within said chamber, said switch structure comprising a fixed contact member disposed within and adjacent the upper end of said chamber, a switch-blade support disposed within and near the lower end of said chamber, a switch-blade hinged at one end to said support and having a free end portion frictionally engageable with and disengageable from said contact member, upon said blade being rotated about its hinged connection to said support, and switch-operating means supported on a pivot carried by said blade at a point remote from said contact member and intermediate said contact member and said switch-blade support when the switch is closed, said switch-operating means including a cam finger normally extending from said pivot toward said support and a lever arm normally extending from said pivot toward the free end of said blade, the free end of said lever arm being manually accessible when said door is open, and abutment means against which said cam finger is arranged to bear, said cam finger being rotatable about said pivot to effect pressure engagement with said abutment means for prying said switch-blade out of engagement with said contact member, rotation of said cam finger about said pivot being effected in response to an outwardly directed pull applied to said lever arm.

2. In a disconnect switch, a housing having an interior chamber and comprising a box made of insulating material and having a frontal opening leading into said chamber, said housing including a displaceable door for said opening, said door providing access to said chamber, and switch structure disposed within said chamber, said switch structure comprising a fixed contact member disposed within and adjacent the upper end of said chamber, a switch-blade support disposed within and near the lower end of said chamber, a switch-blade hinged at one end to said support and having a free end portion frictionally engageable with and disengageable from said contact member, upon said blade being rotated about its hinged connection to said support, and switch-operating means supported on a pivot carried by said blade at a point remote from said contact member and intermediate said contact member and said switch-blade support when the switch is closed, said switch-operating means including a cam finger normally extending from said pivot toward said support, a lever arm normally extending from said pivot toward the free end of said blade, stop means for limiting rotational movement of said switch-operating means about said pivot, and a restoring spring for returning said switch-operating means to its normal position, the free end of said lever arm being manually accessible when said door is open, and abutment means against which said cam finger is arranged to bear, said cam finger being rotatable about said pivot to effect pressure engagement with said abutment means for prying said switch-blade out of engagement with said contact member in re-

sponse to an outwardly directed pull applied to said lever arm.

3. In a disconnect switch, a housing having an interior chamber and comprising a box made of insulating material and having a frontal opening leading into said chamber, said housing including a displaceable door for said opening, said door providing access to said chamber, and switch structure disposed within said chamber, said switch structure comprising a fixed contact member disposed within and adjacent the upper end of said chamber, a switch-blade support disposed within and near the lower end of said chamber, a switch-blade hinged at one end to said support and having a free end portion frictionally engageable with and disengageable from said contact member, upon said blade being rotated about its hinged connection to said support, and switch-operating means supported on a pivot carried by said blade at a point remote from said contact member and intermediate said contact member and said switch-blade support when the switch is closed, said switch-operating means including a cam finger normally extending from said pivot toward said support, and a lever arm normally extending from said pivot toward the free end of said blade, at least the free end portion of said lever arm extending outwardly from said switch-blade and through said frontal opening, said free end portion being manually accessible when said door is open, said door having a rear recess to receive and clear the outwardly extending free end portion of said lever arm, and abutment means situated rearwardly of said switch-blade and against which said cam finger is arranged to bear, said cam finger being rotatable about said pivot in response to an outwardly directed pull applied to said lever arm to effect pressure engagement with said abutment for prying said switch blade out of engagement with said contact member.

4. In a disconnect switch, a housing having an interior chamber and comprising a box made of insulating material and having a frontal opening leading into said chamber, said housing including a door for said opening, said door being hingedly connected at the top thereof to the top portion of said box, said door providing access to said chamber, and switch structure comprising a fixed contact member disposed within and adjacent the upper end of said chamber, a switch-blade support disposed within and near the lower end of said chamber, a switch-blade hinged at one end to said support and having a free end portion frictionally engageable with and disengageable from said contact member, upon said blade being rotated about its hinged connection to said support, and switch-operating means supported on a pivot carried by said blade at a point remote from said contact member and intermediate said contact member and said switch-blade support when the switch is closed, said switch-operating means including a relatively short cam finger normally extending from said pivot toward said switch-blade support, and a relatively long lever arm normally extending from said pivot toward the free end of said blade, at least the free end portion of said lever arm extending outwardly from said switch-blade and through said frontal opening, said free end portion being manually accessible when said door is open, said door having a rear recess to receive and clear the outwardly extending free end portion of said lever arm, said recess being situated below the hinged top of said door, and abutment means situated rearwardly of said switch-blade

and against which said cam finger is arranged to bear, said cam finger being rotatable about said pivot, in response to an outwardly directed pull applied to said lever arm, to effect pressure engagement with said abutment means for prying said switch blade out of engagement with said contact member.

5. In a disconnect switch, a housing having an interior chamber and comprising a box made of insulating material and having a frontal opening leading into said chamber, said housing including a door for said opening, said door having a localized recess on the inner side thereof, and switch structure disposed within said chamber, said switch structure including a switch-blade pivoted within the lower end of said chamber and projecting upwardly from its pivotal point when the switch is closed, and an arm carried by said blade and projecting outwardly therefrom through and beyond said frontal opening into said door recess when the switch and door are closed, the free end of said arm being remote from said blade and adapted for engagement by a switch stick for opening and closing the switch, the arrangement being such that the free end of said arms is readily accessible for opening the switch when said door is open.

6. In a disconnect switch, a fixed contact member, a switch-blade support remote from said fixed contact member, a switch-blade hinged to said support and operative to frictionally engage said contact member, said blade being rotatable about said support to make and break contact with said contact member, and switch-operating means carried by and pivotally connected to said blade at a pivotal point remote from said contact member and intermediate said contact member and said support when the switch is closed, said switch-operating means including a relatively long lever arm projecting normally in a direction generally toward the free end of said switch-blade and also laterally therefrom, said switch-operating means also including a relatively short lever arm normally projecting from said pivotal point toward said support and operative in the nature of a cam to engage an abutment for prying said switch-blade out of engagement with said contact member, said lever arms being rotationally interconnected through said pivotal point whereby a force applied to the end of said long lever arm and directed away from said blade is transmitted in amplified magnitude to the end of said short lever arm and thence to said abutment in a direction effective to move said blade toward open position.

7. In a disconnect switch, a fixed contact member, a switch-blade support remote from said fixed contact member, a switch-blade hinged to said support and operative to frictionally engage said contact member, said blade being rotatable about said support to make and break contact with said contact member, a pivot carried by said switch-blade and located at a point intermediate said contact member and said support when the switch is closed, an element carried by said pivot and rotatable thereabout in a plane substantially parallel to the plane of rotation of said switch-blade, said element including a relatively long lever arm normally projecting from said pivot in a general direction toward the free end of said switch-blade, at least a portion of said lever arm normally projecting laterally from said switch-blade, said laterally projecting portion being adapted for switch-operating engagement with a switch stick, said element also including

a relatively short lever arm normally projecting from said pivot in a direction generally toward said support, an abutment against which said short lever arm bears, stop means for limiting the angle of rotation of said element, and a spring continuously urging said element toward its normal position, said element being operative in response to a force applied to the free end portion of said long lever arm in a plane and direction tending to rotate said element out of its normal position to convert said force into a force of amplified magnitude at the point of contact between said short lever arm and said abutment, said short lever arm and abutment being so correlated that the aforementioned amplified force tends to move said switch-blade out of engagement with said fixed contact member.

8. Electric switch structure comprising: a first fixed contact member, a switch-blade support remote from said first contact member, a second fixed contact member including an abutment, said second contact member being remote from said first contact member and disposed intermediate of said first contact member and said

support, a switch-blade hinged at one end to said support and operative to span and frictionally engage said contact members, said switch-blade being rotatable into and out of engagement with said contact members, a pivot carried by said switch blade at a point intermediate the ends thereof and near said second contact member, and switch-operating means carried by said blade and rotatable about said pivot, said switch-operating means including a cam finger extending from said pivot in a direction generally toward said support and operative to engage and press against said abutment in a direction adapted to pry said switch-blade out of engagement with said contact members, a relatively long lever arm connected with said cam finger through said pivot and extending from said pivot in a direction generally toward the free end of said switch-blade, the free end portion of said lever arm being manually accessible, and stop means for limiting the angle through which said switch-operating means is rotatable about said pivot.
